Charles B. Mann, Jr.
ATTORNEY

UNITED STATES PATENT OFFICE

JACOB SMALL, OF BALTIMORE, MARYLAND

SHIRT FORM

Application filed May 19, 1931. Serial No. 538,406.

This invention relates to an improved construction of shirt form and is especially designed as a form for shirts having attached collars.

5 The object of the invention is to provide a simple and inexpensive form for soft shirts with attached collars, whereby the shirt may be folded about the form and an extension from the latter may be projected up into the 10 rear of the folded collar to hold the collar in an outwardly-inclined position with respect to the folded body of the shirt.

By means of my invention, when the form has been applied to the shirt and the latter 15 packed in a box, the collar of each shirt will incline outwardly from each shirt-body and present a pleasing appearance in addition to preventing the collar from being mashed down flat.

20 The invention is illustrated in the accompanying drawing wherein,—

Fig. 1 shows the device in a flat condition.

Fig. 2 illustrates the same in edge view.

Fig. 3 shows the device with the collar- 25 supporting portion folded and in readiness to be inserted in the fold of the collar.

Fig. 4 illustrates the same in edge view.

Fig. 5 shows a rear view of a portion of a 30 shirt with the form at the rear thereof and the collar-support inserted in the fold at the rear of the collar and in readiness for the body of the shirt to be folded over the form.

Fig. 6 illustrates a front view of a shirt 35 with its attached collar and with the form in place, and

Fig. 7 shows an edge view of the same to indicate how the collar is held in an outwardly-inclined position.

Referring to Figs. 1 to 4 inclusive of the 40 drawing, the numeral 10 designates a flat bosom-board which, in this instance, is of a rectangular shape, and is preferably produced from a comparatively heavy card-board.

45 At the upper edge 11, the bosom-board has a central extension 12 with parallel side edges 13, and with tongues 14 and 15 respectively at opposite corners of its free edge 16. These 50 tongues 14 and 15 are therefore located at,

and form the juncture between, said free edge 16 and the side edges 13 of the extension.

A score line 17 is formed crosswise of and at the base of the extension so the latter may readily be bent forwardly, as will presently be explained.

55 A second score line 18 also extends crosswise of the extension from one side edge 13 to the opposite side edge thereof, and a third score line 19 also extends crosswise of the said extension from one side edge to the other and between the score line 18 and the free edge 16 of said extension.

60 The score lines 17, 18 and 19 across the extension are therefore parallel.

Below, but adjacent to the upper edge 11 65 of the bosom-board 10, the latter is provided with two inclined slits 20,—one of said slits being inclined in a direction reversed to that of the other slit, and each slit is located in 70 the board 10 immediately below the base of one of the side edges 13 of the extension.

75 Attention is directed to the fact that the distance between the score lines 17 and 18 is slightly greater than the distance between score lines 18 and 19.

It will also be noted that the distance between the score line 19 and the free edge 16 of the extension is greater than the distance between any two of said score lines.

80 The purpose of these unequal distances between the score lines across the extension will presently be explained.

The score lines 18 and 19 form fold lines crosswise of the extension so that the free 85 edge portion of said extension may be turned backwardly and downwardly on the score lines 18 and 19.

90 By reference to Fig. 3, the broken line 16 indicates the position the free edge of the extension takes when the same is folded back against the back of the board 10, while the broken line 19 in said Fig. 3, indicates the position of the fold 19 when said extension is turned back.

95 When the side tongues 14 and 15 of the extension are brought into engagement with and passed outwardly through the slits 20, that portion 21 of the extension located between the score lines 17 and 18, must incline 100

forwardly, while the portion 22 between score lines 18 and 19 of the extension will form an outwardly-extending brace to hold the portion 21 forward.

5 The portion 23 at the rear of the board, with the portions 21 and 22, together form a triangular brace and the tongues 14 and 15, when engaged in the slits 20, will therefore hold the triangular brace in the inclined position, substantially as shown in Fig. 4.

10 In applying the form to a shirt 24, the latter is laid out flat, front down, and the fold edge 18 of the triangular brace is inserted up into the collar 25 at the rear thereof, as 15 shown in Fig. 5. This requires the rear of the collar to assume an up-standing and forward-leaning position.

15 The body of the shirt is next folded over the opposite side edges 26 of the form and 20 against the back of the latter and the sleeves are turned in and included in the folds. Finally, the skirt of the shirt is folded up around the lower edge 27 of the form so that the latter will be almost entirely concealed 25 within the folded shirt.

20 The folded edges of the shirt are sometimes pinned together and when the operation is completed, as shown in Figs. 6 and 7, the shirt will be retained in a neatly-folded condition 25 about the form while the collar will be retained in a semi-upstanding position that presents a pleasing appearance.

25 When the form is in place, the shirts may be packed in a box, or displayed or handled without becoming mussed or wrinkled.

30 Obviously, the forms may be cut from a single cardboard and kept flat for shipment and storage purposes.

35 To make the flat form ready for use, the extension may readily be folded on the score lines 18 and 19 and the free edge 16 turned back and held in the turned-back position by engaging the tongues 14 and 15 in the slits 20.

40 Having described my invention, I claim,—
45 1. A form for shirts having attached collars, said form comprising a bosom-board having spaced slits therein adjacent to one edge and at said edge said board having an extension with cross-folds therein and with 50 its free edge turned back against the board, said free edge having a tongue at each side to engage the slits in the board, the distance between the folds and the free edge of the extension being such as to form an inclined 55 brace when the tongues thereon are engaged with the said slits.

60 2. A form for shirts which latter have attached collars, said form comprising a bosom-board with a hollow support extending cross-wise thereof and projecting wholly beyond the board and its top edge, said hollow support having its free edge turned under the board and secured to the latter and also having two cross-folds both of which are beyond both the board and its top edge whereby the 65

extension may be inserted in the rear of a folded collar which is attached to the shirt and hold the rear portion of the collar in an up-standing position.

In testimony whereof I affix my signature.

JACOB SMALL.
